UNITED STATES PATENT OFFICE.

WARREN W. CARPENTER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,247,371.

Specification of Letters Patent. Patented Nov. 20, 1917.

Application filed December 30, 1916. Serial No. 139,896.

To all whom it may concern:

Be it known that I, WARREN W. CARPENTER, a citizen of the United States, residing at Newark, in the county of Essex and State 5 of New Jersey, have invented certain new and useful Improvements in Telephone-Exchange Systems, of which the following is a full, clear, concise, and exact description.

This invention relates to telephone 10 exchange systems employing automatic switches, and more particularly to control circuits for governing the operation of such switches.

It is the object of this invention to provide a simple method of controlling switches which operate reverse impulse senders in response to their movement.

In a well-known type of sender, a set of counting relays is actuated in response to 20 the movement of the switch controlled by them, these relays being successively energized by the action of a stepping relay. In the usual arrangement of this type of sender, the stepping relay is energized and deenergized for each step made by the switch under operation.

A feature of the present invention is an arrangement by which a stepping relay is energized during one step of the switch being 30 operated and is deenergized during the next step of the switch being operated. As a result of this operation less counting relays may be employed and the operation is simpler and more accurate.

35 An additional feature of this invention is a counting relay arrangement in which one of the relays in the set is not energized when even numbers are being sent, but is energized when odd numbers are being sent, 40 therefore, operation of the chain of counting relays may start with a desired relay in the chain and a varying number of impulses will be sent, dependent upon whether the number to be sent is odd or even.

45 It is thought that the invention will best be understood from the following detailed description, reference being had to the accompanying drawings.

In the drawings, Figure 1 shows a selector 50 switch having features in accordance with the present invention; and Fig. 2 shows a sender including a set of counting relays and a control switch therefor, together with a pair of registers to control such sender.

55 The general structure and operation of

the switch shown in Fig. 1 is broadly similar to that shown in Patent No. 1,168,319, to A. E. Lundell, differing only in the construction of the commutator. The construction of the commutator used in the present 60 case will be described hereinafter. The sequence switches and registers are of a type similar to those disclosed in the above mentioned patent.

The operation of the system is as follows. An operator, one of whose cord circuits is indicated at 0, may plug into a calling line jack 1 in response to any well-known line signal. The insertion of plug 2 into jack 1 completes a circuit for cord relay 3 from grounded battery connected to the sleeve of jack 1, through the windings of a cut-off relay, sleeve of plug 2, winding of relay 3 to ground. It has not been considered necessary to disclose the cut-off relay of 75 the calling line, since this is an arrangement well-known in the art. The energization of relay 3 completes a circuit from grounded battery, power magnet of sequence switch 100, contact 102, armature and front 80 contact of relay 3 to ground, which moves sequence switch 100 from position 1 to position 2 under the control of its normal 85 spring 101.

After plugging in, the operator will depress listening key 4, thereby connecting her head set into circuit with the calling subscriber. She may then converse with the calling subscriber and be informed of the number of the wanted line. Assuming that the called subscriber may be reached through an office, the trunks leading to which terminate in the second sub-group of the fifth main group of trunks served by the switch shown in Fig. 1, the operator will 95 depress office key 5 and digit keys in accordance with the designation of the wanted line. Since, however, we are not concerned with the operation of succeeding switches, these keys have not been shown.

A circuit is now completed for relay 6 from grounded battery, winding of relay 6, closed right-hand contacts of key 5 to ground. Relay 6 is energized and completes a circuit from grounded battery, 105 power magnet of district brush register sequence switch 300, right-hand armature and contact of relay 7, armature and contact of relay 6 to ground. A parallel circuit is completed from grounded battery, power magnet 110

of district group register sequence switch 400, right-hand armature and contact of relay 8, armature and contact of relay 6 to ground. Registers 300 and 400 are moved 5 out of the positions in which they last came to rest and continue to rotate until they arrive in positions determined by the contacts controlled by key 5. When the district brush register 300 arrives in position 4, a 10 circuit is completed from grounded battery, winding of relay 7, contact 301, closed left-hand contacts of key 5 to ground. Relay 7 is energized, breaking the circuit of power magnet of brush register 300 and the register is brought to rest in position 4. When 15 district group register 400 arrives in position 1, a circuit is completed from grounded battery, winding of relay 8, contact 401 closed right-hand contacts of key 5, to ground. Relay 8 is energized and breaks at 20 its right-hand armature the circuit of the power magnet of register 400, which is then brought to rest in position 1. Similar registers, not shown, are controlled by the digit 25 keys. After all the registers have been positioned a circuit is completed from grounded battery, winding of power magnet of sequence switch 200, contact 202, left-hand armature and front contact of relay 7, left- 30 hand armature and front contact of relay 8, through the left-hand armatures and front contacts of register controlling relays corresponding to relays 7 and 8 to ground, for moving sequence switch 200 out of position 35 1 and into position 2 under the control of its normal contact 201.

With sequence switch 100 in position 2 and sequence switch 200 in position 2, a circuit is completed from grounded battery, 40 winding of stepping relay 9, contact 203, conductor 10, contact 103, winding of relay 11, conductor 12, contact 204, outer armature and back contact of the 0' counting relay to ground.

45 The energization of relay 11 completes a circuit from grounded battery, winding of relay 14, left-hand armature and front contact of relay 11 to ground. Relay 14 is energized in this circuit and completes a 50 circuit from grounded battery, power magnet of sequence switch 100, contact 104, left-hand armature and front contact of relay 14 to ground, which moves sequence switch 100 out of position 2 and into position 3.

55 In position 3 of sequence switch 100, a circuit is completed from grounded battery, winding of power magnet 18, sequence switch contact 105, left-hand armature and front contact of relay 14 to ground and the 60 brush rod 15 is moved upwardly, carrying with it brush sets 16 and a set of commutator brushes 17. During this movement, the brushes are moved into a position wherein one of the five sets of brushes 16 carried 65 by rod 15 may be tripped.

The energization of relay 9 completes a circuit from grounded battery, armature and front contact of relay 9, right-hand armatures and back contacts of counting relays Nos. 0, 2, 4, 6 and 8, contact 205, contact 70 206, conductor 13, winding of the No. 5 counting relay to ground.

When sequence switch 100 leaves position 2½, relay 9 is deenergized, but relay 11 is maintained energized over a circuit from 75 grounded battery, contact 106, conductor 19, commutator 20, brush 21, right-hand armature and front contact of relay 11, winding of relay 11, conductor 12, contact 204, outer armature and back contact 0' counting 80 relay to ground. The deenergization of relay 9 completes a circuit from grounded battery, armature and back contact of relay 9, right-hand armatures and back contacts of counting relays Nos. 1 and 3, right-hand armature and front contact of counting relay 85 No. 5, winding of counting relay No. 4, to ground.

When commutator brush 22 engages a conducting portion of commutator 23, which will occur at the same time that brush 21 moves onto an insulating segment of commutator 20, relay 9 will again be energized over a path from grounded battery, winding of relay 9, contact 203, conductor 10, contact 90 107, conducting segment of commutator 23, brush 22, right-hand armature and front contact of relay 11, winding of relay 11, conductor 12, contact 204, outer armature and back contact of the 0' counting relay to 95 ground. The energization of relay 9 completes a circuit from grounded battery, armature and front contact of relay 9, right-hand armatures and back contacts of counting 100 relays Nos. 0 and 2, right-hand armature and front contact of counting relay No. 4, winding of counting relay No. 3, to ground. Counting relay No. 3 is energized in this 105 circuit.

When brush 21 engages the second conducting segment of commutator 20, stepping relay 9 will be deenergized, relay 11 remaining energized over a path to grounded battery through contact 106 as previously traced. The second deenergization of relay 9 results 115 in the completion of a circuit from grounded battery, armature and back contact of relay 9, right-hand armature and back contact of the No. 1 counting relay, right-hand armature and front contact of the No. 3 counting relay, 120 winding of the No. 2 counting relay to ground. The No. 2 counting relay is energized in this circuit.

When brush 21 engages the second insulating segment of commutator 20, at which 125 time brush 22 will engage the second conducting segment of commutator 23, relay 9 will be energized as before, and a circuit will be completed from grounded battery, right-hand armature and back contact of the 130

No. 0 counting relay, right-hand armature and front contact of the No. 2 counting relay, winding of the No. 1 counting relay to ground.

- 5 When brush 21 engages the third conducting segment of commutator 20, stepping relay 9 will again be deenergized, completing a circuit from grounded battery, armature and back contact of relay 9, right-hand armature and front contact of the No. 1 counting relay, contact 207, contact 301, conductor 24, winding of the 0' counting relay to ground. 70
- 10

The energization of the 0' counting relay 15 interrupts the circuit of relay 11, and this relay deenergizes. Relay 14 will, however, be maintained energized over a circuit from grounded battery, winding of relay 14, conductor 25, brush 26, conducting portion of 20 commutator 27, conductor 28, right-hand armature and front contact of relay 14 to ground, until the brush 26 engages an insulating portion of commutator 27. When this occurs relay 14 will deenergize, opening at 25 its left-hand armature the circuit for up drive magnet 18. Upon the deenergization of magnet 18, the brush rod 15 comes to rest with the fifth brush set in a position to be tripped. The action of brush 26 over com- 30 mutator 27 prevents the brush rod from coming to rest before the brush sets have been accurately positioned.

Each of the counting relays when energized locks itself to grounded battery through 35 contact 208, through its left-hand armature and remains energized until sequence switch 200 leaves position 2.

When the 0' counting relay was energized, a circuit was completed from grounded bat- 40 tery, power magnet of sequence switch 200, contact 209, outer armature and front contact of the 0' counting relay to ground, for moving sequence switch 200 out of position 2 and into position 4.

45 When relay 14 deenergizes a circuit is completed from grounded battery, power magnet of sequence switch 100, contact 108, left-hand armature and back contact relay 14, to ground, for moving sequence switch 50 100 out of position 3 and into position 4.

At this time sequence switch 200 is in position 4, sequence switch 100 is also in position 4, and brush 22 is engaging the lower-most conducting segment of commutator 29.

55 A circuit will then be completed from grounded battery, winding of stepping relay 9, contact 203, conductor 10, contact 103, winding of relay 11, conductor 12, contact 204, outer armature and back contact of the 60 0' counting relay to ground. Relays 9 and 11 are energized in this circuit.

Relay 11 again completes an energizing circuit for relay 14 from grounded battery, winding of relay 14, left-hand armature and 65 front contact of relay 11 to ground. Relay

14 is energized and completes a circuit from grounded battery, power magnet of sequence switch 100, contact 104, left-hand armature and front contact of relay 14 to ground, for moving sequence switch 100 out of position 4 and into position 5. 70

Relay 9 upon energization completed a circuit from grounded battery, armature and front contact of relay 9, right-hand armature and back contact of counting relays 75 Nos. 0, 2, 4, 6 and 8, contact 210, contact 211, conductor 30, winding of counting relay No. 1 to ground. Counting relay No. 1 is energized and locks up as previously described.

When sequence switch 100 leaves position 80 41, relay 9 will be deenergized, but relay 11 will be maintained energized over a circuit from grounded battery, contact 109, commutator 29, brush 22, right-hand armature and front contact of relay 11, winding 85 of relay 11, conductor 12, contact 204, outer armature and back contact of the 0' counting relay to ground.

While sequence switch 100 is passing through positions 4 to 5, a circuit is completed from grounded battery, winding of tripping magnet 34, contact 111 to ground. The energization of tripping magnet 31 operates a trip rod 32 to release the fifth set 90 of brushes. 95

When sequence switch 100 arrives in position 5, a circuit will be completed from grounded battery, winding of up-drive magnet 18, contact 105, armature and front contact of relay 14 to ground. The brush rod 100 100 is now moved upwardly in its group selecting movement.

When stepping relay 9 was deenergized, as a result of sequence switch 100 leaving position 41, a circuit was completed from 105 grounded battery, armature and back contact of the relay 9, right-hand armature and front contact of the No. 1 counting relay, contact 212, contact 213, conductor 33, winding of the No. 0 counting relay to ground. 110 Counting relay No. 0 is energized and locks up as described.

When brush 22 engages the first insulating segment of commutator 29, which will occur simultaneously with the engagement of 115 brush 21 with the first long conducting segment of commutator 20, stepping relay 9 will again be energized over a circuit from grounded battery, winding of stepping relay 9, contact 203, conductor 10, contact 110, conductor 19, commutator 20, brush 21, right-hand armature and front contact of relay 11, winding of relay 11, conductor 12, contact 204, outer armature and back contact of the 0' counting relay to ground. 120

The energization of stepping relay 9 completes a circuit from grounded battery, armature and front contact of relay 9, right-hand armature and front contact of counting relay No. 0, winding of the 0' counting 125 130

relay to ground. Counting relay 0' is energized and locks itself to grounded battery through contact 208.

Upon energization the 0' counting relay 5 breaks at its outer armature and back contact the holding circuit of relays 9 and 11, since brush 22 is at this time engaging an insulating segment of commutator 29.

Relay 11 at its left-hand armature breaks 10 one branch of the energizing circuit of relay 14, but relay 14 is maintained energized over a locking circuit from grounded battery, winding of relay 14, conductor 25, brush 26, conducting portion of commutator 27, conductor 28, right-hand armature and front contact of the relay 14 to ground, until brush 26 engages an insulating portion of commutator 27, which will occur upon the completion of the second group stop. Relay 14 will 15 then deenergize, opening at its left-hand armature the circuit of up-drive magnet 18. The deenergization of magnet 18 allows the brush rod 15 to be brought to rest with the proper set of brushes accurately positioned 20 below the second group of terminals served by it.

The deenergization of relay 14 also completes a circuit from grounded battery, power magnet of sequence switch 100, contact 108, left-hand armature and back contact of relay 14, to ground, for moving sequence switch 100 out of position 5 and into position 11.

The energization of the 0' counting relay 35 also completed a circuit from grounded battery, power magnet of sequence switch 200, contact 209, outer armature and front contact of the 0' counting relay to ground, for moving sequence switch 200 out of position 40 4 and into position 6.

It is to be understood that trunk hunting occurs in some position of sequence switch 100 between 5 and 11, and upon completion of the hunting movement sequence switch 100 45 is moved into position 11. Since this is a well-known operation, it has not been considered necessary to disclose it in the present description.

With sender sequence switch 200 in position 50 6, and district sequence switch 100 in position 11, the fundamental circuit is completed to a succeeding switch through contacts 112, 113 and brushes 50 and 51. The operation of the sender in setting the succeeding switches is similar to that described 55 and need not be described further. When the last set of impulses has been sent, sequence switch 200 is moved out of its last sending position upon the energization of 60 the 0' counting relay, and is moved into its first or normal position.

Upon arriving in its normal position, a circuit is completed from grounded battery, power magnet of sequence switch 100, contact 114, conductor 36, contact 214 to ground,

for moving sequence switch 100 out of position 11 and into position 16, which is the talking position.

Upon the completion of conversation the operator is informed by the lighting of well-known supervisory signals (not shown), that connection is no longer desired, and she removes plug 2 from jack 1, whereupon relay 3 is deenergized, completing a circuit from grounded battery, power magnet of sequence switch 100, contact 115, armature and back contact of relay 3, to ground, for moving sequence switch 100 out of position 16 and into position 18.

In position 18 of sequence switch 100 a 80 circuit is completed from grounded battery, winding of power magnet 37, contact 116, to ground. The brush rod 15 is restored to normal position under the control of magnet 37, and upon reaching its normal position 85 a circuit is completed from grounded battery, power magnet of sequence switch 100, contact 117, conductor 38, commutator segment 39, brush 40, to ground, for moving sequence switch 100 out of position 18 into 90 position 1.

The succeeding switches are restored in the well-known manner upon the release of the switch shown in Fig. 1.

What is claimed is:

1. In a sending system, a counting device, actuating circuits therefor, variably operable controlling contacts, and means to actuate said counting device to an extent determined in part by certain ones of said controlling contacts and determined in part by others of said controlling contacts in accordance with whether the number to be counted is odd or even.

2. In a sending system, an impulse counting device, actuating circuits therefor, variably operable controlling contacts, and means to actuate said counting device to an extent determined in part by certain ones of said controlling contacts and in part by others of said controlling contacts in accordance with whether the number of impulses to be counted is odd or even.

3. In a telephone exchange system, an automatic switch, a sending device for controlling the operation of said switch, said sending device including a counting device and a relay to control the action of said counting device, and means to energize said relay only during alternate steps of said switch.

4. In a telephone exchange system, an automatic switch, a sending device for controlling the operation of said switch, said sending device including a plurality of counting relays and a stepping relay to control the successive actuation of said relays, and means to energize said stepping relay only during alternate steps of said switch.

5. In an automatic telephone exchange 130

system, a sender arranged to transmit a plurality of sets of impulses, a controlling switch therefor, means to cause said sender to transmit a set of impulses in various ones of the successive positions of said controlling switch, said sender including a counting device, actuating circuits therefor, variably operable controlling contacts, and means to actuate said counting device to an extent determined in part by certain ones of said controlling contacts and determined in part by others of said controlling contacts in accordance with whether the number of impulses to be counted is odd or even.

6. In a telephone exchange system, an automatic switch, a sending device for controlling the operation of said switch, said sending device including a counting device, actuating circuits therefor, variably operable controlling contacts and means to actuate said counting device to an extent determined in part by certain ones of said contacts and determined in part by others of said contacts in accordance with whether the number of impulses to be counted is odd or even, a relay to control the actuation of said counting device, and means to energize

said relay only during alternate steps of said switch.

7. In a sending system, a plurality of counting relays, actuating circuits therefor, variably operable controlling contacts, and means to successively actuate said counting relays, the number of relays actuated being determined in part by certain ones of said controlling contacts and determined in part by others of said controlling contacts in accordance with whether the number of impulses to be sent is odd or even.

8. In a sending system, a register, contacts controlled thereby, a plurality of counting relays, means to successively actuate certain ones of said relays, the number of relays actuated being determined in part by the condition of certain ones of said register controlled contacts and in part by the condition of others of said register controlled contacts, in accordance with whether the number of impulses to be counted is odd or even.

In witness whereof, I hereunto subscribe my name this 28th day of Dec., A. D. 1916.

WARREN W. CARPENTER.
